Application June 17, 1946, Serial No. 677,376

14 Claims. (Cl. 33—27)

1

The present invention relates to automatic machinery for the quantity excising of shapes such as discs, etc., from plate material.

Among the objects of our invention is to provide an automatic machine which admits of ready adjustment or setting for the simultaneous fabrication of a plurality of identical blanks of frangible material of any selected size and shape within the range of the machine, said machine being compact and functioning with a minimum number of operating parts, none of which is delicate or apt to become out of order, and the cost of upkeep of which is low.

A machine of the sort to which the invention relates essentially includes a plurality of scribes which are adapted, when brought to bear upon a plate of frangible material, each to inscribe a circle or other closed curve, whereupon the portion within the scribing may readily be removed from the plate.

A feature of the invention is the mounting of the scribes on the lower ends of driving spindles therefor and the rotation through a transmission operated from a cam shaft of said spindles, each rotated through one complete turn to effect a complete closed curve inscription upon the plate.

Another feature is the feed mechanism by which the plate of frangible material is accurately advanced in a step by step movement preparatory to each scribing operation and in steps by which a second set of scribes forms the inscription in the spaces between those effected by the first set.

Another feature is the provision of a lifting mechanism also controlled from the cam shaft by appropriate cams for simultaneously raising the spindles to maintain the scribing tools above the plane of the stock to be inscribed during the feeding operations.

Another feature is the maintenance of a constant pressure of the scribes upon the plate to be inscribed, such pressure to be adjustable, and this is accomplished preferably by corresponding weightings the scribing spindle.

By way of illustration and not limitation, the machine will be considered as it is employed to scribe discs on plates of glass.

In the accompanying drawings in which are shown one of various possible embodiments of the several features of the invention as incorporated in an automatic machine for scribing discs,

Fig. 1 is a plan view of the machine.

Fig. 2 is a side elevation of the machine.

2

Fig. 3 is a cross-sectional view of the scribing device assembly taken along the line 3—3 of Fig. 1.

Fig. 4 is a cross-sectional view on a larger scale of one of the scribing devices taken along the line 4—4 of Fig. 3.

Fig. 5 is a cross-sectional view of the tool holder taken along the line 5—5 of Fig. 4.

Fig. 6 is a cross-sectional view of the device taken along line 6—6 of Fig. 2, and

Fig. 7 is a fragmentary rear elevation of the machine.

The various feeding and scribing operations are performed by mechanisms for the purpose, all mounted on the bed or table surface 14 of the machine which is supported by a conventional frame 15. Illustratively these mechanisms may include a plate feed mechanism, a scribing device assembly including a plurality of scribes each containing a cutting or scratching tool, a drive mechanism therefor and mechanism for lowering the same to and raising it from scribing position.

While the various cams, gears and sprocket wheels for operating the constituent elements of the machine may be arranged in timed relation in any of a multiplicity of possible ways, to be driven by a common motor M preferably under the bed of the machine, a particularly desirable arrangement is shown in Figs. 2 and 6.

Each of the elements of the machine will now be described in detail.

Feed mechanism

35 The feed mechanism comprises a conventional endless fabric conveyor belt 11, the upper or feed run of which travels in a horizontal plane around rollers 12 and 13. The upper surface of the conveyor belt is supported by the bed or table surface 14 of the machine.

An intermittent feed mechanism causes step by step advance of the conveyor belt so that the plate placed thereon will be in proper position for the operation of the scribing tools.

45 The intermittent feed mechanism comprises a conventional ratchet arrangement consisting of a ratchet wheel 23 concentric and rigid with the roller shaft 24, driven in a step by step movement by a pawl 25 on the upper end of lever 26, said lever being pivoted on roller shaft 24 and operated by a connecting rod or pitman 27 pivoted at its lower end to a slide block 28 in a corresponding track 29 in said lever. Slide block 28 is adjusted by means of a threaded rod 30 along lever 26, the position of adjustment of said slide

block determining the throw of lever 26 and consequently the distance the conveyor belt will travel at each stroke of the connecting rod 27.

Connecting rod 27 is pivoted at its upper end to the upper end of lever 31. The lower end of lever 31 is pivotally secured to the frame 15 of the machine as at 32. At slightly above the midpoint of lever 31, a cam roller 33 is rotatably mounted so that it is in constant contact with elliptical cam 34 carried by cam shaft 35 which extends transversely of the machine. Sprocket chain 36 secured at one end to the upper end of lever 31 as at 37, has at its other extremity a counterweight 38 and rests on sprocket wheel 39 which is rotatably mounted to the frame of the machine as at 40. Counterweight 38 causes a constant lateral tension to be exerted on lever 31, thereby holding cam roller 33 in constant contact with elliptical cam 34.

An adjustable gauge stop 16 is mounted on a sliding block 17 in track 18 along the side of the bed 14. Lateral adjustment of said stop is obtained by means of threaded rod 19. Said rod is screwed through a horizontal hole in block 17 engaging the threads therein; and has one end pivotally secured to the extremity of track 18. Rotation of rod 19, thereby causes block 17 to move forward or backward. Transverse adjustment of said stop is obtained by loosening adjustment bolts 21, said bolts holding bifurcated bar 20 which straddle said bolts, to block 17. The gauge stop is adjusted so that when the rear edge of a plate 22 is aligned with said stop, the leading portion 114 of said plate can be moved by the intermittent feed mechanism to the proper position below the first row of scribing devices to allow a blank of the desired size and shape to be inscribed.

Scribing device assembly

It will, of course, be understood that while two scribing device assemblies are shown, each assembly containing three scribing devices, the invention could be embodied in a machine having one or more scribing device assemblies, each containing one or more scribing devices.

Each scribing device assembly consists of a transverse shaft 74 rotatably mounted in bearings 75 on the upper end of the corresponding pair of transversely aligned supports 65. Transverse shaft 74 is connected by a miter gear pair composed of beveled gears 79 and 80 to vertical spindle 81 rotatably supported in bearings 82 and 83 and carried by frame 84. Frame 84 is secured to cross bars 85 by means of set screws 86 which fit into guideways 87 between said cross bars, as shown in Figs. 3 and 4. By loosening set screws 86, the position of frames 84 may be transversely adjusted along the guideways.

The spindle 81 is vertically reciprocable in its bearings in order to lower the scribing tool or die 105 into position of engagement with the plate 22 and to raise said scribing tool after the plate has been inscribed. Beveled gear 80 rests on top of frame 84, as at 88, and surrounds the upper end of spindle 81 to which it is keyed by a key pin 89 fitting into a longer keyway 89 so that the spindle may move vertically a short distance through beveled gear 80.

Fulcrumed at one end to frame 84 as at 90 is a yoke 91 having an extended arm 92. Said yoke is pivotally affixed as at 93 to a follower block 94 which encompasses but is not affixed to the spindle 81. At the end of the extended arm 92 is a vertical rod 95 upon which any desired num-

ber of metal rings 96 may be placed so as to exert any desired constant downward pressure.

A collar 97 is secured to the spindle 81 and between said collar and follower block 94 a frictionless thrust bearing 98 is placed.

Immediately below collar 97 is washer 99 encompassing but not affixed to spindle 81 and resting on the upper edges of a pair of parallel cross bars 70 straddling the spindle.

Removably affixed to the lower end of spindle 81 by set screw 101 is scribing tool holder 102. Horizontally set in said holder 102 is rod 103 containing at one end thereof a chuck 104 into which is inserted a scribing tool or die 105. The position of the chuck end of rod 103 with respect to holder 102 may be varied by means of set screw 106, said adjustment varying the radius of the closed curve to be inscribed.

Consecutive rows of scribing devices are arranged, as shown in Fig. 1, so that the scribing devices in one row are out of registry with those in the adjacent row. This allows the maximum area of a sheet to be inscribed in the minimum number of operations.

Scriber drive mechanism

The scribe drive mechanism consists of a large interrupted gear 107 mounted on cam shaft 35. This gear intermittently drives pinion 108 mounted on shaft 109 journalled in bearings 110 at opposite sides of the frame of the machine. Sprocket wheel 77 is mounted on the rear end of shaft 109 and is connected to scribe drive sprocket wheels 76 mounted on transverse shafts 74 by means of sprocket chain 78, said chain 78 riding on sprocket wheel 111 mounted on arm 112 affixed to the rear frame of the machine by bracket 113. The function of sprocket wheel 111 is to keep sprocket chain 78 taut thereby ensuring simultaneous rotation of the spindles. The tension on sprocket chain 78 may be adjusted by loosening bolt 78a and varying the position of arm 112.

Lifting mechanism

The function of the lifting mechanism is to raise the spindles carrying the scribing tools from the surface of the material being worked, in order to allow a fresh surface to be introduced to said scribing tools. While the tools may be lifted in any of a multiplicity of possible ways, a particularly desirable arrangement is shown in Fig. 2.

The lifting mechanism for the scribing devices preferably includes, in the embodiment shown, four identical cams 41, two of which are mounted on the ends of cam shaft 35 and the other two near the ends of shaft 42 journalled in bearings 43 adjacent to the respective cams and on opposite sides of the frame.

Cam shaft 35 carries sprocket wheel 44 which is drivingly connected to sprocket wheel 45 on cam shaft 42 by means of sprocket chain 46. Sprocket chain 46 rides on sprocket wheel 47, which is mounted on arm 48 affixed to the frame of the machine by means of bracket 49. The function of sprocket wheel 41 is to keep sprocket chain 46 taut, thereby ensuring that cams 41 will turn simultaneously.

Cam shaft 35 carries sprocket wheel 50 which is drivingly connected by means of sprocket chain 51 to sprocket wheel 52 on the reduction gear housing 53, driven by motor M, as best shown in Fig. 6.

Four identical levers 54 are each pivotally mounted at their midpoints to the frame of the machine as at 55, in such a manner that one end

of each lever is in contact with a lifting cam 41 as at 56, and the other end of each of said levers is pivotally connected as at 57 to the lower end of connecting rod 58 across the upper ends of each pair of which are connected by pivots 61 elevator bars 59 and 60 respectively at opposite sides of the machine. Rotation of cams 41 will therefore cause elevator bars 59 and 60 simultaneously to reciprocate vertically.

Connecting rods 58 are maintained in a vertical position in close juxtaposition to the frame of the machine by means of horizontal guide arms 62, each of which has one end affixed to the frame of the machine as at 63 and the other end straddling the associated connecting rod 58 as at 64, but not affixed thereto. A vertical guide bar 66 is affixed to each of the supports or standards 65 on the outer face thereof. Vertically aligned in close juxtaposition but not attached to said guide bars, are four lifting bars 69, the upper ends of each transversely aligned pair of lifting bars being joined by a pair of parallel cross bars 70 passing through openings 67 in supports 65 and straddling bars 69.

At the lower end of each of the four lifting bars 69 is a tappet 71 adjustable in length, those at one side of the machine resting upon elevator bar 59 and those at the other upon elevator bar 60.

Affixed to either side of lifting bar 69 near the lower end thereof, are brackets 72, the ledge of each of said brackets containing adjustable tappets 73 which come in contact with the ledge of angle bar 68 on the outside base of support 65. The function of said tappets is to ensure that the scribing tools, when they are in a lowered position, will always be out of contact with the conveyor belt in the event that there is no plate intervening between the scribing tool and the conveyor belt.

Operation

The operation of the specific machine shown may be briefly summarized as follows: Depending upon the size of the disc desired, rods 103 are adjusted so that a disc or other curve of the desired size will be inscribed. By varying the adjustment of said rods, discs of different size may be simultaneously inscribed by the machine. If a larger disc is desired than can be secured by the maximum available extension of rod 103, said extension being limited by the proximity of the adjacent scribing tools, frames 84 may be moved transversely by loosening set screws 86 and sliding said frames in the guideways 87. Gauge stop 16 is so adjusted that when a plate 22 is placed in position on the conveyor belt 11, the forward motion of said conveyor belt will place the leading portion 114 of the plate in the proper position with respect to the scribing tools so that the first row will be inscribed as close to the leading edge of the plate as possible.

Depending upon the thickness and type of material to be scribed, in the embodiment shown, a greater or lesser number of rings 96 is placed over rod 95 so as to cause a constant downward pressure of required magnitude to be exerted by the scribing tools when they are in contact with said material. The fabric conveyor belt forms a yielding base for the plate, thereby permitting efficient scribing operations to be performed. One such initial adjustments are made, the machine is ready for automatic scribing operation.

The motor M is started and a frangible plate is

placed upon the conveyor belt so as to be positioned by the gauge stop 16. Motor M through reduction gears 53 rotates sprocket wheel 52 which through chain 51 and sprocket wheel 50 drives cam shaft 35. As lever 31 is held in contact with elliptical cam 34 carried by said cam shaft by means of the lateral pull exerted by counterweight 38, rotation of cam shaft 35 causes lever 31 to move forward and backward, imparting this same motion to lever 26 by means of connecting rod 27. Movement of lever 26 in a counter-clockwise direction causes pawl 25 at the top of said lever 26 to engage ratchet wheel 23 and turn roller 12 a short distance in a counterclockwise direction, thereby moving the conveyor belt and the plate thereon so that the leading portion of said plate is beneath the first row of scribing tools.

The distance the conveyor belt should travel at each throw of lever 26 is determined by the size of the discs to be inscribed and is regulated by means of adjustable block 28 on lever 26.

Cam shaft 42 is rotated from cam shaft 35, thereby causing lifting cams 41 on the latter to rotate with those on the former. Each cam 41 engages the associated lifting levers 54 which in turn causes connecting rods 58 to be raised, thereby raising elevator bars 59 and 60 simultaneously. The two pairs of lifting bars 69 resting at their tappet ends 71 on the respective elevator bars 59 and 60 cause the parallel pairs of cross bars 70 which are connected to said lifting bars 69 to be raised, and to engage and raise spindles 81 by their engagement with washers 99, thereby lifting all the scribing tools 105 from the work.

Lifting cams 41 are so set that when the conveyor belt is advanced by lever 26, the lifting cams will have raised the scribing devices. Cam shaft 35 also turns the interrupted gear 107 thereon, which drives pinion 108 and with it shaft 109 and sprocket wheel 77. Interrupted gear 107 is so placed that it does not mesh with pinion 108 until the scribing tools are in a lowered position in contact with the plate on the halted conveyor belt. When the pinion does rotate, it turns shaft 109 and with it sprocket wheel 77 which through chain 78 drives sprocket wheels 76 to turn transverse shafts 74 which, by means of a miter gear pair 79 and 80, effects rotation of spindles 81 and also holder 102 connected thereto.

When spindle 81 has rotated exactly 360°, interrupted gear 107 no longer meshes with pinion 108 and therefore pinion 108 and scribe drive sprocket wheel 77 are no longer turning. Thus there is assured the completion of the circular or other closed curve inscription without gap or overlap between the ends of the inscribed curve, a feature essential to satisfactory results. At this time lifting cams 41 are in position and raise the scribing tools from the plate by transmission means from said cams to lifting bars 69 which engage and raise spindles 81 and the scribes attached thereto, whereupon the foregoing cycle of operations is repeated.

Forward movement of the conveyor belt carries the plate thereon from the scribing position beneath the first row of scribing devices to the scribing position beneath the second row of scribing devices which are out of registry with the former, so that closed curves can be inscribed in the spaces between the already inscribed portions.

When the frangible plate is completely inscribed, it then receives straight-line scribings 75 between the inscribed circles, to facilitate "pinch-

ing" or breaking out as is customary, whereupon the discs are then freed by knocking away the protruding margins which break away clear at the scribed periphery.

Obviously where the blank to be scribed is not circular, as for instance, where it is elliptical, oval, ovoid, square, hexagonal or octagonal, with or without rounded vertices, a correspondingly shaped fixed cam determines the path of movement of the tool carrying spindle in manner that is thoroughly conventional so that description thereof is unnecessary.

As many changes could be made in the above construction and many apparently widely different embodiments of this invention could be made without departing from the scope of the claims, it is intended that all matters contained in the above description or shown in the accompanying drawings shall be interpreted as illustrative and not in a limiting sense.

Having thus described our invention, what we claim as new and desire to secure by Letters Patent of the United States is:

1. A machine for scribing a plurality of discs simultaneously on a plate or frangible material, said machine comprising a feed therefor, means for intermittently advancing said feed in steps corresponding to the diameter of the discs to be inscribed, a plurality of adjacent scribing device assemblies, each extending transversely of said feed, each of said assemblies including a plurality of scribing devices, the scribing devices in each assembly being out of registry with the scribing devices of the adjacent assembly, each scribing device including a scribing tool normally spaced from said plate, means for lowering said plurality of scribing tools into contact with said plate, means for moving said plurality of scribing tools in a closed path to inscribe discs on said plate after each stepping movement of said feed, means for raising said plurality of scribing tools from said plate after said discs have been inscribed, and timed cam and gear controls driven by a common motor for operating said aforementioned means in sequence.

2. An automatic machine for scribing a plurality of discs simultaneously on a plate of frangible material, said machine comprising a feed therefor including a conveyor belt of yielding material, means for intermittently advancing said conveyor belt longitudinally of said machine in steps corresponding to the diameter of the discs to be inscribed, a plurality of adjacent scribing device assemblies, each extending transversely of said conveyor belt, each assembly including a plurality of scribing devices, the scribing devices in each of said assemblies being out of registry with the scribing devices in an adjacent assembly, each scribing device including a scribing tool normally spaced from said plate, means for varying the diameter of said discs, means for regulating the pressure of said scribing tools on said frangible plate, means for lowering said plurality of scribing tools into contact with said plate, means for moving said plurality of scribing tools through an arc of 360 degrees to inscribe a closed curve on said disc, and means for lifting said scribing tools from said plate after said closed curve has been inscribed.

3. The combination set forth in claim 2 in which the means for advancing said intermittent feed mechanism comprises rollers on which said conveyor belt is mounted, a ratchet wheel affixed to one of said rollers and rotating therewith, a lever pivotally mounted to said roller, said lever

having a pawl at one end thereof to engage said ratchet wheel, an adjustable slide block in said lever, a pitman connected at one end to said slide block, a lever pivotally attached to the other end of said pitman and pivotally attached to the frame of the machine, a cam roller mounted on said last named lever, an elliptical cam in contact with said cam roller, a counterweight connected to said last named lever so as to exert constant lateral pull thereagainst thereby retaining said cam roller against said elliptical cam, and means to rotate said elliptical cam.

4. The combination set forth in claim 2 in which the scribing tool consists of a scratching die affixed to the end of a spindle vertically mounted in bearings in a supporting frame and rotatable therein.

5. The combination set forth in claim 2 in which the means to move said scribing tools through an arc of 360 degrees comprises a plurality of rotatably mounted transverse shafts operatively connected respectively to said tools in each of said assemblies, each of said shafts having a sprocket wheel mounted on the rear end thereof, a sprocket chain connecting said sprocket wheels and means for driving said sprocket chain.

6. The combination set forth in claim 2 in which the means for varying the diameter of the discs includes a scribing tool holder having a horizontally extendable arm supporting said scribing tool, said arm being adjustable in length, the position of the scribing device carrying said scribing tool being transversely adjustable with respect to said conveyor belt.

7. The combination set forth in claim 2 in which the means for raising and lowering said plurality of scribing tool devices includes pairs of vertically reciprocating cross bars, each of said pairs of cross bars being in contact with the plurality of scribing tool devices contained in each of said scribing tool assemblies thereby raising and lowering said scribing tool devices.

8. The combination set forth in claim 2 in which the means for moving said plurality of scribing tools simultaneously through an arc of 360 degrees includes a plurality of transverse shafts associated respectively with each of said scribing device assemblies and mounted on bearings placed on supports straddling said conveyor belt, a vertical spindle slidably mounted in each of said scribing devices, a bevel gear at the upper end of each of said spindles keyed thereto and slidably mounted thereon, a plurality of complementary bevel gears affixed on said transverse shaft, meshed respectively with the bevel gears on said spindle, said scribing tool being carried by the lower end of each of said spindles, and means intermittently to rotate said transverse shafts through one complete revolution.

9. The combination set forth in claim 2 in which each of said scribing devices has a vertical spindle slidably mounted therein carrying said scribing tool at its lower end and the means for regulating the pressure of each of said scribing tools on said frangible plate includes a yoke pivotally affixed at one end to each of said scribing devices respectively, said yoke having near its mid-point a follower block freely encompassing said spindle, means rigid with said spindle against which said follower block is positioned to exert downward pressure thereagainst, said yoke having a substantially horizontal extending arm, and means to vary the pressure on said arm so as to exert any desired constant pressure on said plate.

10. A machine for scribing blanks on plates

of frangible material, said machine comprising a frame having a bed, one or more scribing device assemblies rising from said bed, each of said assemblies including a scribing device having an upright slidably mounted spindle, a scribing tool affixed at the lower end of each of said spindles laterally spaced from the axes thereof and normally spaced from said plate, means to rotate said spindles to move said scribing tools through an arc of 360 degrees to describe the peripheries of the blanks, cross bars operatively connected to the spindles in each of said assemblies respectively, a cam shaft and a transmission from said cam shaft operatively connected to said cross bars to lift the latter and the spindles when said tools have completed their 360 degrees movement, thereby moving said tools from said plate to permit introduction of a fresh area to be inscribed.

11. The combination set forth in claim 10 in which the transmission for lifting said cross bars comprises vertical lifting bars connected to said cross bars, a tappet at the lower end of each of said lifting bars, horizontal elevator bar means supporting said lifting bars at the tappet ends thereof, lever means driven by the cam shaft for lifting said elevator bars, said tappets being adjustable in length, thereby enabling the height to which the cross bars can be raised to be varied so that frangible plates of diverse thickness may be placed beneath said scribing tools. 20

12. The combination set forth in claim 10, in which each scribing device assembly is carried by a pair of transversely aligned supports mounted on the bed of said machine, the outside base of each of said supports having a ledge and in which the cross bars are lifted by vertical lifting bars connected to said cross bars, said lifting bars each having a bracket affixed to either side thereof near the lower end of said lifting bar, the ledge of each bracket containing tappets which come in contact with the ledge on the outside base of said supports, said tappets being adjustable in length and so regulated that the scribing tools when they are in a lowered position, will not contact the conveyor belt. 35

13. The combination set forth in claim 10 in which the means to rotate said upright spindles 45

comprises a plurality of rotatably mounted transverse shafts, said shafts being drivingly connected to the spindles in the respective assemblies, a sprocket wheel connected to the rear end of each of said shafts, a sprocket chain connecting said plurality of sprocket wheels, a sprocket wheel driving said sprocket chain, said sprocket wheel being mounted on the rear of a shaft journaled in bearings under the bed of the machine, a pinion carried by said shafts, an interrupted gear driving said pinion, said interrupted gear being mounted on a cam shaft journaled in bearings under the bed of the machine.

14. The combination set forth in claim 10 in which the transmission for lifting said cross bars comprises lifting bars connected to said cross bars, horizontal elevator bar means supporting said lifting bars, and lever means driven by a common cam shaft for lifting said elevator bars. 15
